AIRPLANE

Jacob Wagner, Seattle, Wash.

Application February 8, 1941, Serial No. 378,049

2 Claims. (Cl. 244—13)

This invention relates generally to aviation and particularly to the heavier than air type of flying machine.

The main object of this invention is to construct a high speed plane having a relatively great carrying capacity.

The second object is to construct a plane of the class described in which all of the air from the slip stream as well as from the forward movement of the plane is utilized for lifting purposes.

The third object is to create a plane having the maximum amount of lateral stability.

The fourth object is to construct a plane which will present the minimum amount of resistance to the air.

The fifth object is to construct a plane of the class described in which a direct elevating action takes place at the forward end of the plane.

I accomplish these and other objects in the manner set forth in the following specification as illustrated in the accompanying drawing, in which:

Fig. 1 is a side elevation of my improved form of airplane.

Fig. 2 is a plan of the airplane with a portion of one of the wings broken away.

Fig. 3 is a section taken along the line 3—3 in Fig. 2.

Fig. 4 is a front elevation of the plane.

Fig. 5 is a transverse section taken along the line 5—5 in Fig. 2.

Similar numerals refer to similar parts throughout the several views.

Referring in detail to the drawing there is shown a fuselage 10 whose forward end 11 is provided with a concave tunnel 12 on its underside, whose upper side 13 extends from the forward edge 14 to the rearward edge 15. The edge 15 is widened laterally to form the tail members 16 whose lateral edges 17 merge gradually into the lower edge 18 of the forward end 11. Extending transversely across the bottom of the tunnel 12 is an air foil 19 which constitutes a support for the motor 20.

An elevator 21 is mounted in the rear of the foil 19 and operated by suitable controls (not shown). The usual form of landing wheels 22 and 23 are also indicated.

Extending laterally from the edges 18 are the wings 24 each of which is provided with motors 25. Motors 20 and 25 are equipped with suitable propellers 26. Ailerons 27 are provided for the wings 24.

The controls of such devices are so well under-

stood that it will not be illustrated or explained here.

At the rear of the tail 16 is attached the elevator 28 and the rudder post 29 has attached thereto 5 a rudder 30 which is disposed midway along the breadth of the elevator 28 and directly above same.

It will be seen that in the operation of this plane, the air is drawn by the propellers 26 producing a definite direction on the airplane, and in addition, this same air is directed together with the surrounding air to converge within the tunnel 12 and along the supporting surfaces of the wings 24 producing the desired lifting and sustaining action.

It will be noted that the overall width of the airplane is relatively small but its supporting area, namely, the surfaces of the tail 16 and the underside of the tunnel 12, extend well to the 10 rear of the wings 24.

In other words, the structure of the tail 16 and the walls of the tunnel 12 does not offer additional resistance as would increased wing length, thereby reducing the power requirements necessary to fly the airplane.

Attention is drawn to my former Patent No. 1,956,054, dated April 24, 1934, over which the airplane described herein is an improvement as far as speed, load carrying ability, and flying is concerned, although it is possibly less stable than the plane described in my former patent.

Attention is especially drawn to the fact that with the present construction, the forward elevator 21 is placed behind the air foil 19 which is in 35 front of the axis of the forward landing wheels 22, while the rearmost elevator 28 is behind the axis of the rearmost landing wheels 23. It is clear that the additional lift provided by the forward elevator 21 will greatly assist in taking 40 off and in landing an airplane, especially one built along the lines herein described and illustrated.

I claim:

1. An airplane having in combination an 45 elongated fuselage having elongated central wings extending along the length of said fuselage and terminating in a widened tail at its rearward end and having its forward end arcuately curved on its underside to form a longitudinal tunnel 50 thereunder, wings projecting laterally from the lowermost portions of the forward end of said fuselage and having lateral ailerons on the outermost trailing edges thereof and a central elevator disposed in front of said lateral ailerons at the 55 lowermost side of said tunnel, elevators disposed

at the rearward end of the longitudinal wings, landing gear disposed on the underside of said fuselage and motor driven propellers disposed in front of said central elevator and along the leading edges of said lateral wings.

2. An airplane of the class described having in combination an elongated central wing having a concave underside forming a wind channel thereunder, a widened tail provided with elevators, the concave underside of said wing having maximum depth at the extreme forward end and a minimum depth near the rearward end of said cen-

tral wing, a propeller unit disposed within the channel, an air foil constituting a brace across the lower edge of the channel and also forming a support for said propeller unit, a central elevator mounted behind said air foil and lateral wings extending from the lower edges of the forward end of said central wing, the outermost trailing edges of said lateral wing having ailerons thereon disposed laterally of and behind said central elevator.

10 JACOB WAGNER.
